UNITED STATES PATENT OFFICE.

EDWARD C. RIES, OF KANSAS CITY, MISSOURI.

JAR-CLOSURE.

1,323,723.

Specification of Letters Patent.

Patented Dec. 2, 1919.

Application filed May 7, 1919. Serial No. 295,281.

To all whom it may concern:

Be it known that I, EDWARD C. RIES, a citizen of the United States, residing at Kansas City, in the county of Jackson, and

5 State of Missouri, have invented certain new and useful Improvements in Jar-Closures, of which the following is a specification, reference being had to the accompanying drawings.

10 This invention relates to the art of jar closures, and particularly to a closure, in which a novel construction of securing means for the closure is involved.

It has been found that using the type of 15 closure particularly used on jars known as the Mason, great difficulty is experienced in removing and applying the closure, necessitating the use of a spanner wrench. Furthermore, when a wrench is not used, it would 20 require heating the closure, to rupture the tight fit.

The present invention aims to avoid these disadvantages by providing a jar having means for supporting yieldable members, 25 for urging constant pressure yieldably on the closure, in combination with means, whereby this pressure may be increased or decreased, and yet at the same time provide a jar closure construction which may be 30 easily opened, and also to provide one that can be easily applied to the jar, and further to insure requisite sealing of the contents.

The invention further aims to provide 35 supporting means anchored to the neck of the jar and carrying members for exerting yieldable pressure, the closure proper in turn supporting means to coöperate with the members, whereby their combined yieldable tensions may be increased or decreased, 40 whereby the pressure upon the closure may be increased or decreased.

While the design and construction at 45 present illustrated and set forth is deemed preferable, it is obvious that as a result of a reduction of the invention to a more practical form for commercial purposes, the invention may be susceptible to changes, and the right to these changes is claimed, provided they are comprehended within the 50 scope of what is claimed.

The invention comprises further features and combination of parts, as will be herein-after set forth, shown in the drawings and claimed.

55 In the drawings:

Figure 1 is a view in perspective of a fruit

jar showing the improved construction applied.

Fig. 2 is a vertical sectional view through same on line 2—2 of Fig. 1.

Fig. 3 is a plan view.

Fig. 4 is an enlarged detail view of the clamping means to be secured about the neck of the jar, for supporting the yieldable members.

Fig. 5 is a detail view in perspective of the upper open end of the neck portion of the jar.

Referring more especially to the drawings 70 1 designates a fruit jar, which may be any suitable shape or configuration. The jar is provided with a contracted neck 2 having an annular rib 3, and 4 denotes a metallic band designed to fit between the rib and where the body of the jar merges into the neck. 75 This band 4 is constructed from spring metal, and its ends 5 are provided with laterally extending ears 6, to receive a screw or bolt 7, provided with a nut 8, whereby the band may be fitted tightly to the neck of 80 the jar below the rib 3. Rising upwardly from the band and riveted thereto as at 9 are upstanding ears 10. These ears are arranged at points diametrically opposite each other, and their upper portions are twisted, 85 as shown at 11, so that the ears will extend angularly from the circumference of the jar closure.

A closure 12 is provided and has a top wall 13, and an annular flange 14. The 90 marginal edge of the flange 14 has a bead 15, between which and the upper edge of the rib 3 of the neck of the jar, a rubber ring or gasket 16 is interposed, thereby insuring a liquid as well as an air-tight joint between 95 the closure and the jar. The closure telescopes the upper part of the neck, and adjacent the inner surface of the top of the closure a porcelain lining 17 is arranged. This lining 17 is secured in the closure adjacent its top wall by means of the bulges 18 formed in the flange of the closure, and constitutes a reinforcement for the closure. Rising upwardly and concentrically with the closure is a threaded stud 19, on which a 100 wing thumb nut 20 is threaded.

Pivotaly mounted in the upstanding ears 10 of the band 4 are bail members 21. These bail members are designed to be constructed of suitable spring steel material, and their 110 hook ends are pivoted in the ears. After the closure is applied to the neck of the jar,

so as to engage the rubber gasket or ring between its beaded edge, and the rib, the bail members are disposed, so that their arms will overly and contact with the marginal 5 upper edge of the closure, as indicated at 22, and so that the central parts of the arches of the bails will be disposed under the wing nut. It is to be noted that when the nut is adjusted sufficiently so as to bear down upon 10 the bails, which, as shown, are angularly disposed, and engaging the marginal edge of the closure, will bear yieldably and exert pressure on the closure sufficiently, to clamp its lower beaded edge in contact with the 15 gasket or rubber ring, insuring a secure fluid and air-tight joint. By a construction of this kind, it is obvious that when it is desired to open the jar to gain access to the contents thereof, it is a very easy matter to 20 unscrew the wing nut. The pressure will be relieved upon the bails, which are free to be tilted outwardly. A sharp instrument, such as the edge of a knife or the like may then be inserted between the beaded edge and the 25 gasket or rubber ring, breaking the seal therebetween, subsequently to which the closure is free to be lifted or removed from the neck of the jar readily allowing access to the contents.

30 The invention having been set forth, what is claimed as new and useful is:

1. In a jar closure, the combination with the neck of a jar, of a closure fitting the neck, a tight joint between the closure and the neck, diametrically oppositely disposed yieldable loops contacting with and overly- 35 ing the edge of the closure, supporting means for said loops, and means carried by the closure and being adjustably movable in

a vertical direction axially with the closure 40 for coöperating with the yieldable loops to increase or decrease the pressure on the closure.

2. In a jar closure, the combination with the neck of a jar, of a closure fitted thereto 45 and provided with a fluid or air-tight joint therewith, diametrically oppositely disposed U-shaped yieldable members carried on the jar and having their arms overlying and en- 50 gaging the upper marginal edge of the clo- 55 sure, means adjustable axially with the clo- sure and engaging and coöperating with said yieldable members, whereby their yield- able pressures on the closure may be in- creased or decreased, and means for carry- 60 ing the last mentioned means on the closure.

3. In a jar closure, the combination with the neck of a jar having an annular rib, of a closure fitting the neck and having a tight joint with said rib, a threaded upright car- 65 ried by the closure concentrically therewith, diametrically opposed yieldable members having their arms overlying and engaging the marginal edge of the closure, a clamping band around the neck and having means for pivotally supporting said yieldable mem- 70 bers, and a device threaded on the upright and engaging and coöperating with the yieldable members, whereby their combined pressures on the closure may be increased or decreased.

In testimony whereof I hereunto affix my signature in the presence of two witnesses.

EDWARD C. RIES.
